(57) CLAIM

The ornamental design for a bottle opener and flashlight key fob, as shown and described.

DESCRIPTION

FIG. 1 is a bottom perspective view of a bottle opener and flashlight key fob, showing my new design;

FIG. 2 is a top perspective view thereof;

FIG. 3 is front view thereof;

FIG. 4 is a rear view thereof;

FIG. 5 is a left side view thereof;

FIG. 6 is a right side view thereof;

FIG. 7 is a bottom view thereof;

FIG. 8 is a top view thereof; and,

FIG. 9 is a top perspective view thereof, shown with a key chain.

The broken lines depicting a key chain in FIG. 9 show environmental subject matter only and form no part of the claimed design.
